[57] **CLAIM**

The ornamental design for a simulative doll bed, as shown and described.

DESCRIPTION

FIG. 1 is a perspective view of a simulative doll bed showing my new design;

FIG. 2 is a top plan view thereof;

FIG. 3 is a bottom plan view thereof;

FIG. 4 is a left side elevational view thereof;

FIG. 5 is a right side elevational view thereof; and

FIG. 6 is another perspective view thereof.

The broken line showing of a doll figure is for illustrative purposes only and forms no part of the claimed design.

FIG. 1

FIG. 3

FIG. 2

FIG. 4

FIG. 5

FIG. 6
